UNITED STATES PATENT OFFICE.

GEORGE KERN, OF PERU, ILLINOIS.

VENDING APPARATUS.

1,225,970.

Specification of Letters Patent. Patented May 15, 1917.

Application filed October 12, 1916. Serial No. 125,302.

To all whom it may concern:

Be it known that I, GEORGE KERN, an alien, former subject of the Empire of Germany, (who has declared his intention to become a citizen of the United States,) and resident of Peru, in the county of La Salle and State of Illinois, have invented certain new and useful Improvements in Vending Apparatus; and I do hereby declare that the following description of my said invention, taken in connection with the accompanying sheets of drawings, forms a full, clear, and exact specification, which will enable others skilled in the art to which my said invention appertains to make and use the same.

My invention relates generally to improvements in vending machines, and it consists, essentially, in the novel and peculiar combination of parts, and details of construction, as hereinafter first fully set forth and described, and then pointed out in the claims.

The object of this invention is the production of an efficient, serviceable, and attractive coin-receiving instrument wherein there are provided means which, when manipulated by a purchaser of certain merchandise or commodity, may entitle the purchaser to a bonus or premium, either in a like merchandise, or other article, as the seller of such merchandise may determine, it being understood that the purchaser, by dropping the proper coin into the apparatus, pays for, and receives at all times, from the vender, the article purchased; and should this coin drop into a certain, predetermined compartment in the apparatus, the purchaser will receive as a discount or premium, such additional merchandise or article as the vender of the commodity purchased, may offer as an inducement to place the coin into the apparatus.

It is a well-established fact that the offer of a premium to a purchaser of merchandise, either in the form of stamps, or coupons, a number of which may be used to purchase certain other articles, promotes trade, a fact which is recognized by many department stores, tobacconists, candy stores, etc., and my invention is based upon this fact. It comprises, therefore, a coin-receiving chamber, superposed by a cover in which there is a coin slot through which the coin is dropped before an article is purchased. This coin drops upon a circular disk, which,

when rotated projects said coin into one of a number of compartments wherein said coin is temporarily retained. One or more of these compartments is, or are, designated the premium-allotting compartment, and if the coin should accidentally drop into this compartment, the purchaser is entitled to his premium, cash discount or other bonus.

The compartments are covered by a transparent, preferably glass, cover, so that the coin when dropping into one of these compartments, may be seen, thereby precluding the possibility of a wrong coin or bogus token being placed into the apparatus without being detected. In these compartments there is a movable bottom, which when depressed, drops the coin into the coin-receptacle.

This apparatus is adapted for the vending of all kinds of merchandise, such as cigars, tobacco, cigarettes, candies, and numerous other articles. Nor is the same confined to one particular coin, it being merely a matter of size of the apparatus to accommodate coins of any value up to a twenty-dollar gold piece.

In the drawings already referred to, which serve to illustrate the preferred embodiment of this invention more fully, and form a part of this specification, Figure 1 is an elevation of this improved apparatus. Fig. 2 is a plan of the same. Fig. 3 is a sectional elevation on line 3-3 of Fig. 2. Fig. 4 is a sectional plan on line 4-4 of Fig. 3. Fig. 5 is a plan of the drop bottom employed in this apparatus. Fig. 6 is a sectional view of the same on line 6-6 of Fig. 5. Fig. 7 is an inverted plan of the apparatus. Fig. 8 is a sectional elevation on line 8-8 of Fig. 9, showing part of the apparatus on a slightly larger scale than that on which Fig. 3 is drawn, the drop bottom or spider being shown in depressed condition. Fig. 9 is a plan of the casing of this apparatus, all movable parts being removed therefrom.

This apparatus comprises a, preferably round, casing A, having a bottom 44, to afford a closed compartment or container B, constructed to receive the coins or tokens deposited in this apparatus. Near the medial portion of this casing A, there is an inwardly extending ledge or flange 13, from which ledge radiate toward the center of the apparatus, upwardly inclined bars 14 extending to a horizontal plate 15, a flange

16 extending downwardly and outwardly from the plate 15 to close the upper or inner portions of the spaces between the bars 14, the lower portions of these spaces remaining open, as shown in Fig. 9.

5 The flange or ledge 13 in the casing A, has an inner shoulder 18, and an outer shoulder 19, both shoulders extending upwardly from said flange and the casing respectively.

10 From a number, preferably three or four, of the bars 14, there extend upwardly posts 20, which posts support a dome C; and upon the flange or ledge 13, and inside of the 15 shoulder 19, there rises a transparent, preferably glass, dome D, sufficiently spaced from the bars 14, to afford an annular space 21, above said bars.

15 Centrally from the top member 15 depends a tubular boss 22, in the bore 23 of which is located a pin or bolt 24, having at its upper end a collar 25, and between said collar and the bottom of the bore 23, and surrounding said pin, there is a coil spring 26. To the lower end of this pin 24 there is secured a spider E, forming a bottom for the spaces 17, said spider being shown in detail in Figs. 5 and 6. This spider has a rim 27; and from this rim project upwardly 20 a series of members 28, there being as many 25 of these members 28 as there are spaces 17 in the body of the casing. These members 28 have vertical walls 29, and downwardly-deflected flanges 30, the outer surfaces of 30 which correspond to the inclination of the bars 14, but when in assembled, normal, position, these outer surfaces are slightly below the outer surface of the flaring flange 16, and slightly below the upper marginal 35 edge of the ring or rim 18.

40 In the face of the ledge 13, there are placed numerals or characters 31, which, when the apparatus is in operative condition and the glass dome C in position, may 45 be readily seen through the transparent dome D.

45 Referring to the superstructure, or dome C, Figs. 1 and 3, this dome is of substantially zig-zag transverse section, and comprises a lower section 32, having a laterally-extending flange 33, overlying the upper end 50 of the glass dome D, so as to retain the same in proper position and prevent its removal. Its upper section 34, is smaller in 55 diameter than the lower section 32; and in its top 35, there is a coin slot 36. Centrally in the top 35, there is a bore in which there 60 is rotatably mounted a tubular shaft 37, formed, preferably integrally, with a gear pinion 38. In this top 35 there is a further bore at some distance from the tubular shaft 37; and in this bore is rotatably mounted a shaft 39, at the lower end of which shaft 65 there is secured a gear wheel 40, meshing with the gear pinion 38. At the upper end

of this shaft there is secured a button 41, by which said shaft 39 may be rotated in a manner readily comprehended.

At the lower end of the tubular pinion-shaft there is secured an annular disk or 70 plate 42 overlying the top of the member 15.

75 In the base or casing A, there are a series of lugs or cleats 43, to which the bottom 44 is properly secured. In this bottom there is an opening 46, which opening is closed by a slide or similar means 45, which slide may be locked in closed position by a lock 47, the bail of which passes through lugs or ears 48, one of which is formed on the slide 45, and the other is placed on the bottom 44 in adjacency to the opening 46 therein. This opening affords means for removing the coins from the coin-container B.

80 In the tubular pinion shaft 37 there is removably placed a rod 49, projecting for some distance from the top 35 of the dome C, said rod having a button 50, at its upper end, its lower end bearing upon the collar 25 of the pin or bolt 24. By means of this rod 49 the spider E may be depressed for 85 the object hereinafter to be explained.

85 In order to cause the coin 51 to locate properly in the dome C upon the plate 42, I locate in this dome a plate 54, Figs. 1, and 2, which plate has an opening 55 through 90 which the coin passes. This plate has also two upstanding guards 56, which prevent the coin from accidentally reaching the gearing located in said dome, and centrally 95 it has a hole which serves as a bearing for the lower end of the tubular pinion shaft 37.

100 The operation of this apparatus is, essentially, as follows: Assume this apparatus being used by a tobacconist who sells cigars of different prices, cigarettes, tobacco, pipes, etc.

105 A purchaser desiring to buy a, say 5 cent, cigar drops his nickel into the coin slot 36, which nickel will fall onto the disk 42. By now whirling this disk by the button 41, the coin 51 is projected from said disk and 110 passing underneath the glass dome D, will drop into one of the series of compartments 52, resting against the shoulder 18 upon the flaring surface 30 of the drop-bottom E, where the coin can be readily seen through 115 glass dome D. Should this coin fall into the compartment 53, which I term the bonus compartment, the purchaser, in addition to receiving the purchased article, will then be entitled to receive a bonus, which may be a 120 further article or any other premium which the vendor may be offering to the lucky purchaser. The purchase being completed the vendor pushes the rod 49 by the button 50, which depresses the drop-bottom E and 125 causes the coin to slide off the inclined surface 30, and to drop into the coin-receiving compartment B.

130 It will now be noted that this device is not restricted to coins of a certain denomina-

tion. Should a purchaser desire to obtain an article of the value of 10 cents or more, he deposits the coin of the proper value into the coin-slot, and when the vender has convinced himself that the coin is of correct value, he delivers the article purchased and deposits the coin into the coin receptacle.

By purchasing an article of greater value than the smallest coin unit, for instance, 10 purchasing an article costing 15 cents, the purchaser can drop first a coin of less value into the apparatus and whirl the button; and this coin will then determine whether the purchaser is entitled to the premium. He 15 then completes the purchase by dropping the additional coin into the coin slot; and if more than one coin is required to make up the full amount, he can drop all the additional coins, one after the other, into the 20 coin slot and then whirl the button to project them all at the same time into whatever compartments they may drop, and the vender, having ascertained that the full amount has been deposited, delivers the purchased 25 article.

One advantage derived from the use of this apparatus is that the vender never handles the purchase money, thereby preventing theft by a dishonest employee. This advantage will, in most cases, more than pay for the premium which a purchaser may receive if his coin reaches the premium compartment.

It will be further observed that when this 35 apparatus is attractively made, it will be an ornament on any store counter, and by its attractiveness and novelty, draw trade to the store.

Having thus fully described this invention, I claim as new, and desire to secure to myself by Letters Patent of the United States—

1. In an apparatus of the nature described, the combination, of a coin receptacle, a series of coin-receiving compartments above said coin receptacle, said coin receptacles having movable bottoms, a superstructure on said coin receptacle, a rotatable disk in said superstructure, gearing constructed 45 to rotate said disk, and a coin receiving element in said superstructure through which a coin may be dropped upon said disk and projected into one of said coin-receiving compartments.

55 2. In an apparatus of the nature described, the combination, of a closed coin receptacle, a series of coin-receiving compartments above said coin receptacle, said coin receiving compartments having drop-bottoms, a superstructure on said coin receptacle, means in said superstructure constructed to project a coin into one of said coin-receiving compartments, and means for depressing said bottoms to cause said coin to drop into said coin receptacle.

3. In an apparatus of the nature described, the combination, of a coin receptacle, a series of coin-receiving compartments above said coin receptacle, a coin-receiving element above said coin-receiving compartments, a movable bottom common to all of said coin-receiving compartments, means for projecting a coin deposited in said superstructure into one of said coin-receiving compartments, and means for depressing said movable bottom to cause a coin in one of said coin-receiving compartments to drop into said coin receptacle. 70 75

4. In a structure of the nature described, the combination, of a coin receptacle, a series 80 of coin-receiving compartments above said coin receptacle, a coin-receiving element above said coin receptacle, a transparent cover over said coin-receiving compartments, a coin-receiving element above said compartments, means for projecting a coin deposited in said coin-receiving element into one of said coin-receiving compartments, and means for removing a coin from said coin-receiving compartments and passing it 85 into said coin receptacle. 90

5. In an apparatus of the nature described, the combination, of a coin receptacle, a series of coin-receiving compartments above said coin receptacle, a dome above said 95 coin-receiving compartments, said dome having a coin-slot, a rotatable disk, said disk being horizontally disposed in said dome and adapted to support a coin passed through said coin slot, and means for rotating said 100 disk to project said coin into one of said coin-receiving compartments.

6. In an apparatus of the nature described, the combination, of a coin receptacle, a series of coin-receiving compartments 105 above said coin receptacle, a dome above said coin-receiving compartments, said dome having a coin slot, a rotatable disk, said disk being horizontally disposed in said dome and adapted to support a coin passed through 110 said coin slot, and means for rotating said disk to project said coin into one of said coin-receiving compartments, said means including a shaft supporting said horizontal disk, a gear pinion on said shaft, a further 115 shaft, a gear wheel mounted on the latter shaft and meshing with said gear pinion, and means extraneous of said dome for rotating said gear-wheel shaft.

7. In an apparatus of the nature described, the combination, of a coin receptacle, a series of coin-receiving compartments above said coin receptacle, a dome above said coin receiving compartments, said dome having a coin slot, a rotatable disk, said disk 125 being horizontally disposed in said dome and adapted to support a coin passed through said coin slot, means for rotating said disk to project said coin into one of said coin-receiving compartments, said coin-receiving 130

compartments having each a bottom, and means for depressing said bottoms.

8. In an apparatus of the nature described, the combination, of a coin receptacle, a series of coin-receiving compartments above said coin receptacle, a dome above said coin-receiving compartments, said dome having a coin slot, a rotatable disk, said disk being horizontally disposed in said dome and adapted to support a coin passed through said coin slot, means for rotating said disk rapidly to project a coin into one of said coin-receiving compartments, said coin-receiving compartments having each a bottom, and means for simultaneously depressing all of said bottoms.

9. In an apparatus of the nature described, the combination, of a coin receptacle, a series of coin-receiving compartments above said coin receptacle, a transparent cover over said coin-receiving compartments, said cover being spaced therefrom to afford a passage for a coin, a superstructure over said coin-receiving compartments, said superstructure having a coin slot, a rotatable disk, said disk being horizontally disposed in said superstructure and adapted to support a coin passed through said coin slot, means for rotating said disk to project said coin into one of said coin-receiving compartments, said coin-receiving compartments having each a bottom, and means for depressing said bottoms.

10. In an apparatus of the nature described, the combination of a coin receptacle, a series of coin-receiving compartments above said coin receptacle, a transparent cover over said coin-receiving compartments, said cover being spaced therefrom to afford a passage for a coin, a superstructure over said coin-receiving compartments, said superstructure having a coin slot, a rotatable disk, said disk being horizontally disposed in said superstructure and adapted to support a coin passed through said coin slot, means for rotating said disk to project said coin into one of said coin-receiving compartments, said coin-receiving compartments having each a bottom, and means for simultaneously depressing all of said bottoms.

11. In an apparatus of the nature described, the combination, of a coin receptacle, a series of coin-receiving compartments above said coin receptacle, a superstructure over said coin-receiving compartments, there being a coin slot in said superstructure, a drop bottom for said coin-receiving compartments, and means for depressing said drop bottom to cause a coin deposited in one of said compartments to drop into said coin receptacle.

12. In an apparatus of the nature described, the combination, of a coin receptacle, a series of coin-receiving compartments above said coin receptacle, a superstructure

over said coin-receiving compartments, there being a coin slot in said superstructure, a drop bottom for said coin-receiving compartments, and means for depressing said drop bottom to cause a coin deposited in one of said coin-receiving compartments to drop into said coin receptacle, said means including a spring device for supporting said bottom in elevated position, and a rod projecting from said superstructure constructed for depressing said bottom.

13. In an apparatus of the nature described, the combination, of a coin receptacle, a series of coin-receiving compartments above said coin receptacle, an inverted-pan shaped element over said coin-receiving compartments, said pan-shaped element having centrally a tubular depending boss, a bolt slidably located in said boss, a drop bottom in said coin-receiving compartments, said drop bottom being secured to the lower end of said bolt, a spring in said tubular boss for holding said drop bottom in normal, elevated, position, and means for depressing said bolt.

14. In an apparatus of the nature described, the combination, of a coin receptacle, a series of coin-receiving compartments above said coin receptacle, an inverted-pan shaped element over said coin-receiving compartments, said pan-shaped element having centrally a tubular, depending, boss, a bolt slidably located in said boss, a drop bottom in said coin-receiving compartments, said drop bottom being secured to the lower end of said bolt, a spring in said tubular boss for holding said drop bottom in normal, elevated, position, means for depressing said bolt, a superstructure above said inverted-pan shaped element, there being in said superstructure a coin slot, and means in said superstructure constructed to project a coin dropped through the said coin slot into one of said coin-receiving compartments.

15. In an apparatus of the nature described, a casing, there being in said casing a coin receptacle, an inverted-pan shaped element over said coin receptacle, a series of bars connecting said casing to said pan-shaped element, thereby affording open spaces between said bars, and a filler in each of said spaces, constructed to afford a bottom for each space and convert these spaces into coin-receiving compartments.

16. In an apparatus of the nature described, the combination, of a casing, there being in said casing a coin receptacle, an inverted-pan shaped element over said coin receptacle, a series of bars connecting said casing to said pan-shaped element thereby affording open spaces between said bars, a filler in said spaces constructed to afford a bottom for each space and convert these spaces into coin-receiving compartments, said fillers being compressible.

17. In an apparatus of the nature described, the combination, of a casing, there being in said casing a coin receptacle, an inverted-pan shaped element over said coin receptacle, a series of bars connecting said casing to said pan-shaped element thereby affording open spaces between said bars, a filler in said spaces constructed to afford a bottom for each space and convert these spaces into coin-receiving compartments, said fillers being compressible, and means for compressing said fillers from the exterior of said casing.

18. In an apparatus of the nature described, the combination, of a casing, there

being in said casing a coin receptacle, an inverted-pan shaped element over said coin receptacle, a series of bars connecting said casing to said pan-shaped element thereby affording open spaces between said bars, a filler in each of said spaces constructed to afford a bottom for each space and convert these spaces into coin-receiving compartments, said fillers being connected to a common support, and means for depressing said support.

In testimony that I claim the foregoing as my invention, I have hereunto set my hand, at Peru, Ill., this 7th day of September, 1916.

GEORGE KERN.
